UNITED STATES PATENT OFFICE.

WILLIAM J. WILTSE, OF LISBON, NORTH DAKOTA.

MILK-PAIL HOLDER.

Application filed January 3, 1927. Serial No. 158,733.

This invention relates to pail holders and more particularly to a holder adapted to support a pail while milking a cow.

One object of the invention is to provide a holder by means of which a pail may be supported while milking without it being necessary to grip the pail between the knees.

Another object of the invention is to so form the holder that a pail supported thereby will be disposed forwardly at a downward incline in the usual position occupied by a pail when milking.

Another object of the invention is to provide a pail holder which may be applied to pails of different sizes.

Another object of the invention is to provide a pail holder formed of resilient wire and, therefore, cheap to produce.

Another object of the invention is to securely connect the end portions of the wire from which the holder is formed by means of a clip which not only serves to secure the ends of the wire but also constitutes a holder in which an advertising card may be placed and supported above the knee in full view of the person using the holder.

Another object of the invention is to provide a pail holder which may be snapped on or off the pail instantly.

Another object of the invention is to provide a holder which will remain in position on the pail while being carried about.

The invention is illustrated in the accompanying drawing, wherein

Fig. 1 is a perspective view of the improved pail holder;

Fig. 2 is an enlarged fragmentary view of the holder;

Fig. 3 is an enlarged sectional view taken on the line 3-3 of Fig. 2, and

Fig. 4 is a sectional view taken on the line 4-4 of Fig. 1.

The pail holder constituting the subject-matter of this invention is formed from a strand of resilient wire having portions thereof curved to form jaws 1 and 2 which cooperate with each other and constitute front and rear sections of the pail encircling portion of the holder. When forming the holder, the wire is first bent intermediate its length to form a U-shaped hanger 3 having a bridge portion 4 from which arms 5 and 6 extend and is then bent to form eyes 7 and 8 from which the curved jaws 1 and 2 extend.

After the jaws 1 and 2 have been formed, the wire is bent to form eyes 9 and

10 and has its end portions extended upwardly and bent to form a second hanger 11 which is also U-shaped and provided with side arms 12 and 13 joined by a bridge portion 14 formed from the extreme end portions of the wire. The forward jaw 1 is of greater length than the rear jaw 2 so that the hangers will not be in exact opposed relation diametrically of the pail encircling portion of the holder and the weight of the pail will cause it to tilt forwardly when in use.

A clip 15 formed of sheet metal is disposed between the arms 12 and 13 of the hanger 11 and has its side and outer end portions rolled to form sleeves 16 and 17.

The sleeves 16 fit tightly about the side arms 12 and 13 of the hanger and the sleeve 17 fits about its bridge portion. It will, therefore, be seen that, when the clip is in place,

the end portions of the wire will be firmly connected and prevented from moving out of proper relation to each other. An advertising card 18 may be placed upon the body portion of the clip or plate 15 and tightly gripped beneath the arms 12 and 13, as

shown in Fig. 4, when the sleeves are formed or an advertisement may be stamped into the body of the clip. It will also be obvious that a patent date may be stamped into the body of the clip. The pail holder may,

therefore, be employed as an advertising medium by a dealer. It should be noted that the rear arms 6 and 13 are shorter than the front arms 5 and 12. This causes the

lower ends of the rear arms to be disposed in a higher plane than the lower ends of the front arms and, therefore, the pail encircling portion of the holder formed by the co-operating sections or jaws 1 and 2 will extend forwardly at a downward incline, as

shown in Fig. 2. It should be also noted that the relation of the hangers to each other diametrically of the pail encircling portion of the holder assists in causing the pail to tilt forwardly. Crimped portions 19 are formed upon the rear arms 6 and 13 to provide latches adapted to extend over the upper edge of a pail and prevent the holder

from dropping off when the pail is carried. In order to retain the jaws in proper position to form a pail encircling portion of the required diameter, there have been provided chains 20 which are carried by the eyes 7

and 9 and adapted to be engaged by hooks 21 carried by the eyes 8 and 10. The hooks will be engaged with the appropriate links

of the chains according to the size of pail to be supported.

When the pail holder is in use, the hooks are engaged with the appropriate links of the chains and the pail fitted between the jaws with the latches 19 engaged over the upper edge of the pail. The curved hangers are then rested upon the legs of the person who is to milk the cow and the pail will be disposed in the usual position between the knees but does not have to be gripped by the knees. Since the rear arms of the hangers are shorter than the forward arms, the pail will be disposed forwardly at a downward incline in the usual position in which a milk pail is held when milking so that the milk may be easily directed into it. By employing the holder it is not necessary to grip the pail between the knees or set it upon the ground beneath the cow and there is less likelihood of the pail being turned over or knocked from between the knees by a cow stamping. After the cow has been milked the pail is grasped by its handle and the holder may be easily slid downwardly out of engagement therewith or may be supported thereon by the latches 19 while the pail is carried to another cow to be milked.

Having thus described the invention, I claim:

1. A pail holder comprising a pail-engaging portion, and hangers extending upwardly from opposite sides of the pail-engaging portion and each having front and rear arms, the rear arms being shorter than the front arms whereby the pail-engaging portion will be supported in a plane extending forwardly at a downward incline.

2. A pail holder comprising a pail-encircling portion having companion front and rear sections movable towards and away from each other, resilient hangers having arms joined to said sections and yieldably resisting movement of the sections towards each other, hooks adjacent the junction of the hangers with the ends of one section, and links adjacent the junction of the hangers with the other section adapted to be engaged with said hooks for releasably retaining said sections drawn towards each other for gripping engagement with a pail.

3. A pail holder comprising a pail-encircling portion having companion front and rear sections movable towards and away from each other, resilient hangers having

arms joined to said sections and yieldably resisting movement of the sections towards each other, said hangers being bent to dispose the pail-encircling portion at a downward incline towards its front, and means to releasably retain said sections drawn towards each other for gripping engagement with a pail.

4. A pail holder comprising a pail-encircling portion having companion sections movable towards and away from each other, hangers carried by said sections and yieldably resisting movement of the sections towards each other, said hangers having front and rear arms joined to the sections and curved longitudinally, the rear arms being shorter than the front arms to dispose the pail-encircling portion at a downward incline towards its front, and means to releasably retain the sections thereof drawn towards each other for gripping engagement with a pail.

5. A pail holder comprising a strand of resilient wire bent to form pail-gripping sections and U-shaped hangers having depending arms joined to said sections and yieldably resisting movement of the sections away from each other, eyes being formed at the junction of the arms and sections, hooks carried by the eyes of one section, and links carried by the eyes of the other section and adapted to be engaged by said hooks to releasably retain the sections drawn towards each other for gripping engagement with a pail.

6. A pail holder comprising a strand of resilient wire bent to form pail-gripping sections and U-shaped hangers having depending arms joined to said sections and yieldably resisting movement of the sections away from each other, the ends of said strand being disposed at the outer end of one hanger, a plate having its side and outer end portions curled about the arms and outer end portion of the last-mentioned hanger to prevent separation of the ends of the strand, said plate being adapted to support a card with edge portions of the card engaged by the curled portions of the plate, and means to releasably hold said sections drawn towards each other for gripping engagement with a pail.

In testimony whereof I affix my signature.

WILLIAM J. WILTSE. [L. S.]
